UNITED STATES PATENT OFFICE

ROBERT S. PEELLE, OF HOLLIS, NEW YORK, ASSIGNOR TO THE PEELLE COMPANY, OF BROOKLYN, NEW YORK, A CORPORATION OF NEW YORK

SELF-BREAKING CANOPY-TYPE DOOR

Application filed October 2, 1929. Serial No. 386,789.

My invention relates to self-breaking canopy type doors, and more particularly to a door of the canopy type in which, when the latch mechanism is released, the weight of the door itself will cause an initial opening movement thereof sufficient to avoid the necessity for the breaking of the joint between the foldable sections of the door by the application of force either manual or mechanical thereto.

Canopy type, bi-fold, or jack-knife, doors are old and well known in the building trades. Such doors usually consist of two sections, the upper of which is hinged above the lintel of a door opening, and the lower of which is hinged to the bottom of the upper door section. The manner of mounting the upper door section has always been such that when a door was closed, the two sections would hang in substantially vertical alignment, being suspended from the hinges connecting the upper section with the wall of a building.

To ensure a tight closing of the door, it has been a common practice to force the two sections slightly beyond the vertical center of the hinged connections between the sections, but whether this practice was followed or not, a door, when closed, was ordinarily so set as to require the exercise of considerable strength to break the hinged joint between the two sections before opening power applied to the door, was operative to complete such opening movement. This condition existed both with manually operative, counterweighted doors, and with doors, the movements of which were mechanically effected by what is known as a door "operator". In fact, various devices have been suggested and used with the so-called automatic doors, or those having a mechanical operator, by which the initial application of power to the door will apply a force adjacent the hinged connection which would break the joint between the sections and thus permit the application of opening power to the door.

The difficulties above referred to arise from the fact that when opening canopy doors, and during the full opening movement, the load of the counterweight, or the power of

the operator, is applied closely adjacent the bottom of the lower door section and exerts a directly vertical pull, this portion of the lower door section, except for the turning action of the door, being a directly vertical movement. Consequently, when the door is closed, this vertical pull had no tendency whatever to start the two sections of the door inwardly of the opening at the hinged connection.

With the above conditions in mind, I have provided a door of the canopy type, in which the upper section is so mounted that it has a normal tendency to swing inwardly of the door, which normal tendency is restrained by a latch mechanism when the door is fully closed. As a result of this construction, when the latch mechanism is released, the two sections will break at their point of pivotal connection of their own accord, without the application of any force thereto by the operator, whether manual or mechanical, and thus permit the application of power to the door, whether by counterweights or by an operator, in a manner which will ensure a smooth, easy operation of the door.

Canopy doors are ordinarily used to close large door openings in warehouses or like buildings, and are fairly large, heavy structures. Consequently, when closing the door, the two sections will gather considerable momentum, even though they may be closely counterweighted, and hence, when closing the door, they will, of their own accord, overcome the normal tendency of the upper door section to swing inwardly of the opening to an extent to permit the automatic action of the latch mechanism, which is relied upon to normally prevent such tendency when the door is closed.

In a door embodying the invention, the construction is such as to further ease the initial opening movement of the door by avoiding possible binding of the pivotal supports for the upper door section, which expedient will also facilitate a close fitting of the door and ease in the automatic closing and latching movement above referred to.

The door of my invention is preferably so constructed as to not only avoid possible

binding between the two sections when the door is closed, but also to guard against the possibility of a person's fingers or hand being caught and squeezed between the two sections when closing the door, the construction in fact being such as to make it impossible for any portion of the hand to accidentally enter the gap between the two door sections during such final closing movement.

10 A safety appliance may also be provided in the door, which will act automatically to prevent the falling of the door in the event of the breakage of the flexible connections, through which the door is operated whether 15 these connections are acted upon by a counterweight or a mechanical door operator.

It is also possible, with a construction of door embodying the invention, to provide a remote control for the latch mechanism, and to so proportion the load of the counterweight to that of the door as to ensure practically an automatic opening movement of the door when releasing the latch mechanism, under which condition the moving inertia of the door is relied upon to overcome the excess load of the counterweight in effecting a complete closing and latching of the door. Of course if an operator be used, this remote control is particularly advantageous.

30 It is not my intention to include the operator feature in the form of invention herein shown and described.

The invention consists primarily in a self-breaking canopy type door embodying there-in a plurality of sections hinged together at one face of the door, a pivotal support for the upper door section adjacent the lintel of the door opening, the axis of which support is offset from the plane of the door at the face thereof opposite the hinged connection between the sections, a keeper adjacent the door jamb, a latch member carried by one of the door sections co-operating with said keeper, said keeper and said latch member being capable of relative movement in setting and releasing the latch, guides above each jamb of the door, flexible connections passing about said guides and having a swivelling connection adjacent the bottom of the lower section, and means capable of exerting a pull upon said flexible connections; and in such other novel features of construction and combination of parts as are hereinafter set forth and described, and more particularly pointed out in the claims hereto appended.

55 Referring to the drawings,

Fig. 1 is a view, vertically and laterally condensed, of a self-breaking canopy type door embodying the invention;

60 Fig. 2 is a section on the line 2—2 of Fig. 1, with portions broken away to disclose the lintel, sill and one jamb of the door opening;

Fig. 3 is a section on the line 3—3 of Fig. 1;

65 Fig. 4 is a sectional view upon a larger scale of the pivotal support for the upper

door section showing the automatic action of the door in dotted lines; and

Fig. 5 is a sectional view upon a larger scale showing the manner of connecting the upper and lower section and the latch mechanism, and indicating in dotted lines the position of parts automatically assumed when releasing the latch.

Like numerals refer to like parts throughout the several views.

In the embodiment of the invention shown in the drawings, wall angles 10 are mounted upon the wall 11 adjacent the jambs of the door opening, one of the flanges of these angles extending inwardly of the building, as shown in Fig. 3. The door proper is composed of an upper section 12 and a lower section 13, the former of which is hinged in a particular manner above the lintel of the door opening, to be more fully described hereinafter, and the latter of which is connected with the upper section by means of hinges 14 positioned at one face of the door, and so set as to permit the doors to fold in relation to each other during the opening movement of the door, a condition common to canopy type doors.

Above each wall angle 10 is a guide sheave 15, about which sheaves pass chains 16 or other suitable flexible means for controlling the movements of the door, which have a swivelling connection adjacent the bottom of the lower door section 13 at opposite sides thereof, so that the force applied to the door through these connections is in a directly vertical line.

100 Mounted adjacent the bottom of the lower door section is a thrust roller 17 engaging one flange of the wall angles 10, these rollers being commonly used for the purpose of permitting ease of movement of the door when opening and closing same, notwithstanding the thrust of the door sections toward the wall of the building, incidental to canopy type doors.

105 The sheaves 15 may be attached to a metallic wall plate 18 secured to the wall 11 above the door opening. Also carried by this wall plate 18 are a plurality of hinge plates 19, the number and dimensions of which will 110 vary according to the size and weight of the door.

115 Ordinarily, doors of the canopy type will be about two inches in thickness when metal sheathed wood panels are used, although with all metallic doors, this thickness of course will be materially less. The door shown in the drawings is of the wood panel type.

120 The socket portion 20 of each hinge plate 19 is projected from said plate so as to be offset from the plane of the face of the door opposite that to which the hinges 14 are connected.

125 Secured to the upper door section 12 are

hinge straps 21, connected by means of hinge pins 22 with the socket portions 20, said hinge straps being offset in relation to the face of the door against which they bear. Preferably, the straps 21 are provided with elongated enlarged openings 23, the hinge pins 22 having a driving fit with the socket portion 20. The offset socket portion 20 and similarly offset strap 21 afford sufficient play in the knuckle joint of the hinge to ensure a free turning movement of the upper door section 12, and permit a slight vertical movement of the entire door in relation to the hinge plate 19, which is desirable in a door embodying the invention.

The offset hinge structure 20, 21 and 22 affords pivotal suspension means for the upper door section 12 sufficiently at one side of the center line of the door, when it is in the fully closed position, to permit the utilization of the weight of this door section, and of the force of gravity, to impart an initial opening movement to the door sufficient to break the joint at the hinge 14 between the sections 12 and 13. This is due to the fact that the off-center pivotal support afforded by said hinges 20, 21 and 22 results in a normal tendency of the door section 12 to assume a position at an angle to the wall 10, the movement of the bottom portion of the section 12, as it assumes its angular position, being away from the wall. The quantity of such movement is determined by the extent to which the pivot 22 is offset in relation to the vertical plane of the door when it is closed and locked.

Adjacent each door jamb is a latch keeper 24, secured to the flange of an angle 25, which in turn is riveted or otherwise attached to the inwardly directed flange of the wall angle 10 with which the latch member is associated. These keepers 24 co-operate with a latch mechanism carried by one of the door sections, the lower section 13 as shown in the drawings, for the purpose of preventing the action of gravity upon the upper door section 12, in the manner above described.

This latch mechanism, in the form of the invention shown, comprises a rocking shaft 26 carried by the door section 13, having an operating handle 27 centrally thereof and offset latch members 28 adjacent the opposite ends of said bar and engageable with the keepers 24 respectively. The location of this latch mechanism is largely a matter of convenience, it being merely necessary that it be so located and so constructed that when the door sections 12 and 13 are in substantially vertical alignment, the latch members 28 will engage the keepers 24 and prevent a gravity return movement of the section 12 and a responsive return movement of the lower section 13.

It is preferable to employ a latch member at each side of the door, and a rock shaft carrying the latch members is used in order

to permit the simultaneous operation of both latches.

Each keeper 24 is provided with a striker 29 for ensuring the proper engagement of a latch member 28 with its cooperating keeper.

Any suitable means, as a stop 30, may be used for preventing such movement of the shaft 26 as might interfere with the proper latching action when the door reaches the fully closed position.

In the form of the invention shown, the chains or other flexible connections 16 are acted upon by a weight 31 substantially counterbalancing the weight of the door sections 12 and 13 and their appurtenances. If desired, this weight 31 may slightly overbalance the door sections, so that when the latch mechanism is released, the opening of the door will be entirely automatic. With a close balancing of the door and the counterweight, the release of the latch mechanism with a slight force applied to the door, inwardly of the wall, will cause the door to fully open of its own accord. Overweighting of the counterweight 31 merely ensures this movement of the door without the application of that slight force thereto. The counterweight 31 represents merely a force applied adjacent the bottom of the lower door section for the purpose of assisting in or causing the opening movement of the door, and permitting an easy closing movement thereof as a result of the restraint upon the doors by the counterweight. The doors otherwise could not be maintained in the open position, but would close by gravity with sufficient violence, by reason of the weight of the doors, to make the use of such doors impossible.

Doors in actual use, in some instances, have been equipped only with a counterweight for developing the necessary operating power. In other instances, electrical operators have been used with and without a counterweight. Consequently, the counterweight shown in the drawings may be considered merely as a source of power for developing a desired lifting action upon the door sections in opening the door, and checking downward movement of the sections by gravity, in closing the door.

In some instances it may be desirable to provide a remote control for the latch mechanism, and under such conditions I provide a solenoid 32, the core of which is provided with an extension 33 engageable with the end of one of the latch members 28, the circuit for energizing said solenoid being controlled by a switch mechanism 34 conveniently located for the purpose.

It is a common practice, with stevedores working around canopy doors, to assist the final closing movement of the door by pushing against same adjacent the meeting line of the two door sections, and there is always

70

110

115

120

125

130

likelihood of injury to the hand or fingers by having them caught and crushed between the bottom edge of the upper section and the top edge of the lower section. To guard against possibility of such injury to workmen, the bottom of the upper section, and the top of the lower section are spaced apart when assembling the door, thus affording clearance sufficient to receive the fingers, or a portion of the hand, without developing any severe crushing strains thereon. I supplement this action by providing a light metallic astragal secured to one of the door sections and lapping the other, thus effectively protecting the gap between the two door sections and preventing the accidental insertion of the hand or fingers between these sections.

The space between the two sections is indicated in the drawings at 35, and the light yieldable astragal is shown at 36. This astragal is carried by the lower door section and is spaced away from the face of the door a sufficient distance so that the upper edge thereof may be grasped by the hand and the door completely closed, without possibility of injury to the hand, particularly in view of the fact that the astragal will yield in the case of the engagement of the hand with the door panel.

Gaps like that shown at 35 are not desirable in an outside door, and to minimize this undesirability and secure a better weather joint, I rabbet both door sections, as shown in Figs. 2 and 5 of the drawings. This rabbetting of the door sections provides a better weather joint and also permits the use of a wider portion of the gap 35 adjacent the astragal 36. This astragal will also aid in securing a better weather joint than would otherwise be present.

The formation of the gap 35 also has the advantage that it avoids any possible binding between the two sections when the door is in the closed position, which binding might interfere with the automatic breaking of the joint between the two sections, which is the main characteristic of the invention.

Instances have been known where the chains 16 become detached from the counterweight, or break. If such should occur, the door would simply drop, and anyone struck thereby would be seriously injured, because of the weight of the door and the speed developed in its downward movement. To guard against such an accident, not withstanding that likelihood of such occurring is very remote, I provide each of the wall angles 10 with a rack bar 37, extending throughout the entire range of movement of the lower door section 13, and utilize, as a part of the swivel connection between the door and the chains, or other flexible connections 16, a spring pressed pivotal dog 38 having a heel to which a chain 16 is connected. With this construction, the load of the counterweight and of the door will overcome the normal tend-

ency of the spring acting upon the dog 38 to engage said dog with the rack bar 37. In other words, the arrangement of weights and connections is such that when the door is in proper condition, the dog 38 will be held in a position inoperative in relation to the rack 37, but in the event of the breakage of either or both chains, the dogs will immediately be forced into engagement with the rack bars 37 and thus arrest downward movement of the door.

It has been demonstrated in actual practice, that the thrust of the door sections toward the wall angle 10 and the rack bar 37 will ensure a proper continuing engagement of the dog 38 with a tooth of the rack, when said dog is once engaged therewith by the action of its spring.

The operation of the herein described self-breaking canopy type door is substantially as follows:—

In describing the operation of the door of the invention, it will be assumed that the door is in the fully closed and locked position, as shown in full lines in the drawings. With the parts in this position, the door will be suspended from the hinge pin 22, and by reason of the offset relation of this hinge pin with the plane of the inner face of the door, there will be a constant tendency of the upper section to swing about the hinge pin 22 to the right, Fig. 2, which tendency will be resisted, however, by the engagement of the latch members 28 with the keepers 24.

When counterweights are used, as shown in the drawings, there will be constantly exerted upon the door, through the chains 16, a lifting action applied adjacent the bottom of the lower section 13.

When it is desired to open a door, it is merely necessary to disengage the latch members 28 from the keepers 24, which may be done by actuating the rock shaft 26 by means of the handle 27, or by merely raising one of the latch members. Upon the disengagement of the latch members from their keepers, the upper door section 12 will immediately seek an equilibrium, swinging inwardly of the door opening, or to the right, Fig. 2, the weight of the section 12 being sufficient to cause a similar turning movement of the lower section about the swivel connection between same and the flexible connections 16.

The extent of this turning movement of the two sections may be governed, within limits, by the extent to which the pivot pin 22 is offset in relation to the door.

Since the upper door section may be five feet in height, or even more, with an offset of an inch or so the lower edge of this section may have a movement of three inches or more, which is adequate to effectively break the joint, and to give a starting upward impetus to both sections, accompanied of course by the folding action characteristic of the

canopy type of door. The lower portion of the upper door section 12 naturally will swing beyond its point of equilibrium as the latch members are released, and will not be permitted a return movement.

If the counterweight 31 be such as to exactly balance the doors when in the open position, the breaking action will be followed by a continuing opening movement of the door, which movement, however, will be a slow movement. The action of the upper section when breaking the joint appears to give a starting impetus or impulse to the door, due to the inertia of the counterweight 31 and the slight, but rapid, lift of the lower door section at the bottom thereof, which has the effect of momentarily creating sufficient slack in the chains 16 to permit a jar upon the door as the counterweight takes up this slack. This jar will accelerate the upward movement of the door sections immediately following the initial opening movement caused by the swinging of the upper door section, above referred to. Of course, if the counterweight 31 has a capacity greater than that required to exactly balance the doors, the speed of the opening movement will be greater than with a close counterbalancing by means of the said counterweight.

When the door is once started, the moving inertia of parts will continue the opening movement, and there will be some acquired momentum, this, however, being no factor so far as the opening of the door is concerned.

It will be understood that a vertical pull or stress applied through the chains 16 will cause the bottom of the lower section to move in a vertical line, and that the rollers 17 will resist the thrust imparted to this lower section during the opening movement by the upper section at the hinges 14. This, however, is characteristic of all canopy type doors.

Of course, if desired, the operator may increase the speed of operation of the door by pulling it toward him when actuating the rock shaft 26. This is not necessary, however, under ordinary conditions, but it may be done.

If a mechanical operator be used, such operator will merely supplement the action above referred to, which condition will always be present in the door if a counterweight be used. If, however, no counterweight be used, the mechanical operator is relied upon solely to impart continuing opening movement to the door.

When it is desired to close a door, it is merely necessary to grasp the strap 39, which is carried by all canopy type doors which are to be manually operated, and to pull down upon the door with a short sharp action. As the door descends, with a reversal of the action above referred to, the weight of the

upper door will develop a moving inertia, or will acquire momentum, which, together with the weight of the lower section, will overcome the counterbalancing action of the weight 31, and thus cause a rapid continuing closing movement of the doors by an unfolding action. This momentum will be sufficient to cause the upper door section 12 to pass its point of equilibrium to an extent to cause the latch members 28 to engage the co-operating keepers 24 and thus check a return movement of the door such as follows the release of the latch mechanism when opening the door, the striker 29 actuating the rock shaft to ensure such engagement of the latch members 28 with the keepers.

If the bottom or lower door section be fairly closely fitted to the threshold of the opening, the bottom of the door, in turning, may engage said threshold, but the elongated slot 23 will permit the lifting of the whole door structure to compensate for this action. Said slot, and the opening 35 between the door sections, ensures freedom and ease of movement of both sections when both opening and closing the door.

If, by any chance, the latch members 28 should not engage with the keepers 24, it is merely necessary for the attendant to push the doors toward the wall of the building before they have had a chance to re-open to any substantial extent. The space 35 and the yieldable astragal 36 are provided for the purpose of preventing the hands of an attendant being injured in the event that he does so push the doors. The astragal completely covers the gap 35, and is spaced away from the upper door section so as to afford clearance for the fingers in the event that an attendant should grasp the edge of the astragal. The yieldability of the astragal is to preclude any possibility of the fingers or hand being pinched between same and the upper door section 12.

The use of the solenoid 32 is merely a matter of convenience, it being possible to locate the switch 34 at any convenient point and thus permit the opening of the doors without an attendant being near the door. The effect of the action of the solenoid is the same as though the rock shaft 26 were manually operated.

The action of the rack bar 37 and spring pressed dog 38 need not be described in detail. Such is merely an emergency safety device, and conditions are seldom such as to make it operative.

The essential characteristic of the invention is the construction by which the upper door section, by reason of its weight and manner of mounting same, has a constant tendency to initiate an opening movement of the door, which tendency is restrained by a lock or latch mechanism having the mode of

operation herein referred to, and I intend to claim such broadly.

It is not my intention, however, to limit the invention to the precise details of construction shown in the drawings, it being apparent that such may be varied without departing from the spirit and scope of the invention.

Having described the invention, what I claim as new and desire to have protected by Letters Patent, is:—

1. A self-breaking canopy type door embodying therein a plurality of sections hinged together at one face of the door, a pivotal support for the upper door section adjacent the lintel of the door opening, the axis of which support is offset from the plane of the door at the face thereof opposite the hinged connection between the sections, a keeper adjacent the door jamb, a latch member carried by one of the door sections co-operating with said keeper, said keeper and said latch member being capable of relative movement in setting and releasing the latch, guides above each jamb of the door, flexible connections passing about said guides and having a swivelling connection adjacent the bottom of the lower section, and means capable of exerting a pull upon said flexible connections.

2. A self-breaking canopy type door embodying therein a plurality of sections hinged together at one face of the door, hinge plates secured adjacent the lintel of a door opening, each having a socket portion projected therefrom so as to be offset from the plane of the face of the door opposite the hinged connections between said sections, a hinge pin secured to said socket portion, hinge straps engaging said pins and secured to the upper door section, a keeper adjacent the door jamb, a latch member carried by one of the door sections co-operating with said keeper, said keeper and said latch member being capable of relative movement in setting and releasing the latch, guides above each jamb of the door, flexible connections passing about said guides and having a swivelling connection adjacent the bottom of the lower section, and means capable of exerting a pull upon said flexible connections.

3. A self-breaking canopy type door embodying therein a plurality of sections hinged together at one face of the door, hinge plates secured adjacent the lintel of a door opening, each having a socket portion projected therefrom so as to be offset from the plane of the face of the door opposite the hinged connections between said sections, a hinge pin secured to said socket portion, hinge straps each having a vertically elongated opening through which a pin passes and secured to the upper door section, a keeper adjacent the door jamb, a latch member carried by one of the door sections co-operating with said keeper, said keeper and

said latch member being capable of relative movement in setting and releasing the latch, guides above each jamb of the door, flexible connections passing about said guides and having a swivelling connection adjacent the bottom of the lower section, and means capable of exerting a pull upon said flexible connections.

4. A self-breaking canopy type door embodying therein a plurality of sections hinged together at one face of the door, a pivotal support for the upper door section adjacent the lintel of the door opening, the axis of which support is offset from the plane of the door at the face thereof opposite the hinged connection between the sections, keepers adjacent the door jambs and the hinged connection between the door sections, latch members carried by one of the door sections co-operating with said keepers respectively, each said keeper and said latch member being capable of relative movement in setting and releasing the latch, connections between said latch members, whereby they move in unison, guides above each jamb of the door, flexible connections passing about said guides and having a swivelling connection adjacent the bottom of the lower section, and means capable of exerting a pull upon said flexible connections.

5. A self-breaking canopy type door embodying therein a plurality of sections hinged together at one face of the door, a pivotal support for the upper door section adjacent the lintel of the door opening, the axis of which support is offset from the plane of the door at the face thereof opposite the hinged connection between the sections, keepers adjacent the door jambs and the hinged connection between the door sections, a rock bar mounted upon one of said sections, offset latch members carried by said rock bar and co-operating respectively with said keepers, guides above each jamb of the door, flexible connections passing about said guides and having a swivelling connection adjacent the bottom of the lower section, and means capable of exerting a pull upon said flexible connections.

6. A self-breaking canopy type door embodying therein a plurality of sections hinged together at one face of the door, hinge plates secured adjacent the lintel of a door opening, each having a socket portion projected therefrom so as to be offset from the plane of the face of the door opposite the hinged connections between said sections, a hinge pin secured to said socket portion, hinge straps engaging said pins and secured to the upper door section, keepers adjacent the door jambs and the hinged connection between the door sections, latch members carried by one of the door sections co-operating with said keepers respectively, each said keeper and said latch member being capable

of relative movement in setting and releasing the latch, connections between said latch members, whereby they move in unison, guides above each jamb of the door, flexible connections passing about said guides and having a swivelling connection adjacent the bottom of the lower section, and means capable of exerting a pull upon said flexible connections.

7. A self-breaking canopy type door embodying therein a plurality of sections hinged together at one face of the door, hinge plates secured adjacent the lintel of a door opening, each having a socket portion projected therefrom so as to be offset from the plane of the face of the door opposite the hinged connections between said sections, a hinge pin secured to said socket portion, hinge straps each having a vertically elongated opening 20 through which a pin passes and secured to the upper door section, keepers adjacent the door jambs and the hinged connection between the door sections, a rock bar mounted upon one of said sections, offset latch members 25 carried by said rock bar and co-operating respectively with said keepers, guides above each jamb of the door, flexible connections passing about said guides and having a swivelling connection adjacent the bottom of the 30 lower section, and means capable of exerting a pull upon said flexible connections.

8. A self-breaking canopy type door embodying therein a plurality of sections hinged together at one face of the door, the contiguous edges of said door sections being spaced apart to form a gap of sufficient width to prevent the pinching of the hand or fingers, a pivotal support for the upper door section adjacent the lintel of the door opening, the axis of which support is offset from the plane of the door at the face thereof opposite the hinged connection between the sections, a keeper adjacent the door jamb, a latch member carried by one of the door sections co-operating with said keeper, said keeper and said latch member being capable of relative movement in setting and releasing the latch, guides above each jamb of the door, flexible connections passing about said guides and having a swivelling connection adjacent the bottom of the lower section, and means capable of exerting a pull upon said flexible connections.

9. A self-breaking canopy type door embodying therein a plurality of sections hinged together at one face of the door, the contiguous edges of said door sections being spaced apart to form a gap of sufficient width to prevent the pinching of the hand or fingers, a yieldable astragal carried by one of said sections upon the side thereof opposite to that at which the sections are hinged, a pivotal support for the upper door section adjacent the lintel of the door opening, the axis of which support is offset from the plane of the door at the face thereof opposite the

hinged connection between the sections, a keeper adjacent the door jamb, a latch member carried by one of the door sections co-operating with said keeper, said keeper and said latch member being capable of relative movement in setting and releasing the latch, guides above each jamb of the door, flexible connections passing about said guides and having a swivelling connection adjacent the bottom of the lower section, and means capable of exerting a pull upon said flexible connections. 70

10. A self-breaking canopy type door embodying therein a plurality of sections hinged together at one face of the door, the contiguous edges of said door sections being spaced apart to form a gap of sufficient width to prevent the pinching of the hand or fingers, hinge plates secured adjacent the lintel of a door opening, each having a socket portion projected therefrom so as to be offset from the plane of the face of the door opposite the hinged connections between said sections, a hinge pin secured to said socket portion, hinge straps engaging said pins and secured to the upper door section, a keeper adjacent the door jamb, a latch member carried by one of the door sections co-operating with said keeper, said keeper and said latch member being capable of relative movement in setting and releasing the latch, guides above each jamb of the door, flexible connections passing about said guides and having a swivelling connection adjacent the bottom of the lower section, and means capable of exerting a pull upon said flexible connections. 80 90

11. A self-breaking canopy type door embodying therein a plurality of sections hinged together at one face of the door, the contiguous edges of said door sections being spaced apart to form a gap of sufficient width to prevent the pinching of the hand or fingers, hinge plates secured adjacent the lintel of a door opening, each having a socket portion projected therefrom so as to be offset from the plane of the face of the door opposite the hinged connections between said sections, a hinge pin secured to said socket portion, hinge straps engaging said pins and secured to the upper door section, keepers adjacent the door jambs and the hinged connection between the door sections, latch members carried by one of the door sections co-operating with said keepers respectively, each said keeper and said latch member being capable of relative movement in setting and releasing the latch, connections between said latch members, whereby they move in unison, guides above each jamb of the door, flexible connections passing about said guides and having a swivelling connection adjacent the bottom of the lower section, and means capable of exerting a pull upon said flexible connections. 100 110 115

- bodying therein a plurality of sections hinged together at one face of the door, the contiguous edges of said door sections being spaced apart to form a gap of sufficient width to prevent the pinching of the hand or fingers, a yieldable astragal carried by one of said sections upon the side thereof opposite to that at which the sections are hinged, hinge plates secured adjacent the lintel of a door opening, each having a socket portion projected therefrom so as to be offset from the plane of the face of the door opposite the hinged connections between said sections, a hinge pin secured to said socket portion, hinge straps each having a vertically elongated opening through which a pin passes and secured to the upper door section, keepers adjacent the door jambs and the hinged connection between the door sections, a rock bar mounted upon one of said sections, offset latch members carried by said rock bar and co-operating respectively with said keepers, guides above each jamb of the door, flexible connections passing about said guides and having a swivelling connection adjacent the bottom of the lower section, and means capable of exerting a pull upon said flexible connections.
13. A self-breaking canopy type door embodying therein a plurality of sections hinged together at one face of the door, hinge plates secured adjacent the lintel of a door opening, each having a socket portion projected therefrom so as to be offset from the plane of the face of the door opposite the hinged connections between said sections, a hinge pin secured to said socket portion, hinge straps engaging said pins and secured to the upper door section, keepers adjacent the door jambs and the hinged connection between the door sections, latch members carried by one of the door sections co-operating with said keepers respectively, each said keeper and said latch member being capable of relative movement in setting and releasing the latch, connections between said latch members, whereby they move in unison, a solenoid adjacent one of said latches, an extension upon the core of said solenoid engageable with a latch member, guides above each jamb of the door, flexible connections passing about said guides and having a swivelling connection adjacent the bottom of the lower section, and means capable of exerting a pull upon said flexible connections.
14. A self-breaking canopy type door embodying therein a plurality of sections hinged together at one face of the door, a pivotal support for the upper door section adjacent the lintel of the door opening, the axis of which support is offset from the plane of the door at the face thereof opposite the hinged connection between the sec-

tions, a keeper adjacent the door jamb, a latch member carried by one of the door sections co-operating with said keeper, said keeper and said latch member being capable of relative movement in setting and releasing the latch, guides above each jamb of the door, flexible connections passing about said guides, a vertically extending rack bar adjacent each side of the door, a spring pressed latch dog having a swivelling connection adjacent the bottom of each side of the lower section, and a counterweight, one end of said connections being attached to said dog and the other end thereof to said counterweight.

15. A self-breaking canopy type door embodying therein vertically extending wall angles, an angle at one end of each of said wall angles, a keeper carried by one of the flanges of each of said last named angles, an upper door section, hinge plates above the lintel of a door opening, each having a socket portion projected therefrom so as to be offset from the plane of the face of said door section, a hinge pin secured to said socket portion, hinge straps each having a vertically elongated opening through which a pin passes, secured to said door section, a lower door section hinged at the face of said upper door section opposite to that at which said hinge plate is secured, the contiguous edges of said sections being spaced apart to form a gap of sufficient width to prevent the pinching of the hand or fingers, a yieldable astragal carried by said lower section opposite the hinge connecting said sections, and extending across said gap, a rock bar mounted upon said lower section adjacent the hinged connection between said sections, offset latch members carried by said rock bar and co-operating respectively with said keepers, guide sheaves above each of said angle bars, flexible connections passing about said sheaves and having a swivelling connection adjacent the bottom of the lower section, a thrust roller adjacent the bottom of said lower section, and a counterweight acting upon said flexible connections.

In witness whereof I have hereunto affixed my signature this 28th day of September, 1929.

ROBERT S. PEELE.
